(Cl. D71—1)

To all whom it may concern:

Be it known that I, Griffith Annesley, a citizen of the United States, residing at New York, in the county of New York and State of New York, have invented a new, original, and ornamental Design for a Propeller Hub, of which the following is a specification, reference being had to the accompanying drawing, forming part thereof, wherein:

Fig. 1 is a top plan view of a propeller hub embodying my new design;

Fig. 2 is a front elevational view thereof;

Fig. 3 is a bottom plan view; and

Fig. 4 is a side elevational view.

I claim:

The ornamental design for a propeller hub, as shown.

GRAFFITH ANNESLEY.
